UNITED STATES PATENT OFFICE.

JOHN T. LESHER, OF JORDAN, NORTHUMBERLAND COUNTY, PENNSYLVANIA.

FENCE.

SPECIFICATION forming part of Letters Patent No. 340,795, dated April 27, 1886.

Application filed February 20, 1886. Serial No. 192,628. (No model.)

To all whom it may concern:

Be it known that I, JOHN T. LESHER, a citizen of the United States, residing in Jordan township, in the county of Northumberland and State of Pennsylvania, have invented 5 certain new and useful Improvements in Portable Fences; and I do hereby declare the following to be a full, clear, and exact description of the invention, such as will enable others skilled in the art to which it appertains to make and use the same.

This invention relates to portable fences.

The object of the invention is to produce a fence which shall be capable of being folded 15 into the smallest possible space to facilitate its storage and transportation, which shall be capable of being readily set up with equal facility upon level or uneven ground, and which, although readily moved when set up, will not 20 be affected by strong winds.

With these objects in view my invention consists, essentially, in what may be termed a "fence-post" made up of four legs so connected as to readily be spread apart when in use, and 25 be folded snugly together when it is desired to store or transport them, the said legs being so formed and connected as to enable their relative lengths to be changed at will to adapt the post to uneven ground. Furthermore, the 30 invention consists in various novel details of construction, whereby the effectiveness of the device is increased, and the objects of the invention attained.

I have illustrated the invention in the accompanying drawings, in which Figure 1 represents a side elevation of a section of fence made in accordance with my invention. Fig. 2 is a perspective view of my improved post, showing it in position for use; and Fig. 3 is a 40 side elevation of the post, showing it folded for transportation or storage.

In the drawings, A represents the posts, which are made up preferably of four legs or bars, *a a* and *a' a'*. The legs *a a* are preferably 45 so arranged as to extend in a direction coincident with the length of the fence in which the post is to be placed, and the legs *a' a'* are so joined to the legs *a a* as to be capable of being spread out to extend in a direction opposite to that assumed by the legs *a a*.

For economy in cost, and to render the device simple in construction, the parts are so formed that one bolt serves to hold the parts together, and to form a pivot upon which the legs are turned to spread them out when in use, or to fold them together when it is desired to put them into a compact form for storage or transportation. To this end the upper ends of the legs *a a* are beveled, as shown at *a' a'*, and the bar or bolt B passes through the legs just 55 above the lower end of this bevel. The bolt is provided at one end with a head and at the other with a screw-threaded end upon which is placed a nut, *b*, and a washer, *b'*, which is forced by the nut to bind the parts closely together. 60

When the nut upon the screw-bolt is turned, the upper ends of the legs are moved inward, and thus moving the lower ends outward by reason of working on fulcrums formed by the 65 lower end of the bevel on the portion. The ends *a' a'* are cut away at such an angle that when their beveled faces are in a plane with the face of the legs *a a* the legs *a a* will be spread out in proper position to assist in supporting 70 the post.

The upper ends of the legs *a' a'* are provided with a series of holes, *a' a'*, through which the bolt B passes, and the length of these legs relative to each other and to the legs *a a* is easily regulated by changing the hole in which the bolt rests, and thereby the post may be adapted to 80 the most uneven ground.

The fence-sections used in connection with my improved posts are preferably formed of 85 the horizontal bars or slats C and suitable cross-pieces, C', whereby the said slats are secured together and the desired form of the section preserved.

The preferred means of attaching the section C to the posts is by means of the hooks *a'*, in which the upper slat may be placed and retained by means of the pivoted button *a'*, which may be turned down to press against the slat, and thus retain the section in position. The lower ends of the legs are provided 95 with the notched buttons, which may be turned down to engage with the lower slat, and thus assist in holding the section in place.

My improved fence is particularly advan- 100

tageous to divide off fields and lots in which plowing is to be done, for the reason that by simply swinging one of the legs *a'* up out of the way the ground may be tilled up to the fence.

5 Having thus fully described my invention, what I claim as new, and desire to secure by Letters Patent, is—

1. A fence-post consisting of the four legs, two being beveled at their upper ends, and a bolt passing through the upper ends, substantially as described.

10 2. A fence-post consisting of the four legs, two being beveled at their upper ends, and a bolt passing through the legs near their upper ends and just above the lower end of the bevel, substantially as described.

15 3. A fence-post consisting of the four legs,

two of which are provided near their upper ends with a series of holes, and the other two of which are beveled, and a bolt passing through the upper ends thereof, substantially as described.

4. The combination, in a folding fence-post, of the four legs connected by means of a bolt forming a pivot upon which the legs work, 25 two of said legs being provided with brackets and buttons, substantially as described, whereby fence-sections may be held in place.

In testimony whereof I affix my signature in presence of two witnesses.

JOHN T. LESHER.
